DESIGN FOR A MEDICO-SURGICAL CAMERA CASING

Frederick K. Storm, Los Angeles, Calif., assignor to Adel Precision Products Corp., a corporation of California

Application February 12, 1946, Serial No. 126,517

Term of patent 14 years

(Cl. D61—1)

To all whom it may concern:

Be it known that I, Frederick K. Storm, a citizen of the United States, residing at Los Angeles, in the county of Los Angeles, State of California, have invented a new, original, and ornamental Design for a Medico-Surgical Camera Casing, of which the following is a specification, reference being had to the accompanying drawings, constituting a part thereof.

Fig. 1 is a three-quarter perspective view of a medico-surgical camera casing, showing my new design;

Fig. 2 is a three-quarter rear perspective view thereof;

Fig. 3 is a plan view thereof; and

Fig. 4 is a front elevation thereof.

I claim:

The ornamental design for a medico-surgical camera casing, substantially as shown.

FREDERICK K. STORM.
